Inventor:
JOHN J. POTT,

By
John H. Brumming,
His Attorney.

UNITED STATES PATENT OFFICE.

JOHN J. POTT, OF ST. LOUIS, MISSOURI.

LOOSE-LEAF BINDER.

Application filed May 24, 1922. Serial No. 563,282.

To all whom it may concern:

Be it known that I, JOHN J. POTT, a citizen of the United States, and residing at St. Louis, Missouri, have invented the new and 5 useful Improvement in Loose-Leaf Binders, of which the following is a specification.

This invention relates to loose leaf binders employed for holding sheets or leaves temporarily in book form and constitutes an improvement on the loose leaf binder of Patent 10 No. 1,184,014, patented May 23, 1916.

One of the objects of this invention is to provide a loose leaf binder arranged to hold the leaves or sheets so as to permit manipulation, removal and replacement of the same.

Another object of this invention is to provide a loose leaf binder which is arranged to selectively hold the sheets either so as to permit them to be turned from one back to 20 another or to hold them on one back of the binder.

Another object of this invention is to provide a loose leaf binder which is simple in construction, effective in its action and cheap 25 to manufacture.

Further objects will appear from the detail description taken in connection with the accompanying drawing, in which:

Figure 1 is a perspective view of a binder 30 embodying this invention;

Figure 2 is a section, somewhat enlarged, on the line 2—2, Figure 1;

Figure 3 is a view similar to Figure 2, but showing the employment of a holding 35 head; and

Figure 4 is a still further enlarged detail of Figure 2.

Figure 5 is an enlarged detail of Figure 2 showing the fastening of the threaded 40 post.

Referring to the accompanying drawing, the binder, as shown, comprises a back 1 having sides 2 of paper board or any other suitable material and provided with a covering 45 3 which may be of fabric, leather or any other suitable material, this covering also forming the hinge connections 4.

Incorporated in one of the sides of the back are a base strip 5 of metal or any other 50 suitable material, which extends laterally along the inner face of the side and is turned under as shown at 6. These strips are pressed or sunk into the back and are covered by the covering 3, so as to present a 55 neat and attractive appearance. Secured

near each end, to the strip and the back is a hollow post 7 which is provided with an enlarged shoulder 8 in the form of a washer secured to the post or even integral therewith and bearing on the strip, while the 60 shank of the post passing through the strip and back is riveted or clinched over at 9 so as to be sunk into the back and presenting outside flush surfaces concealed by the covering. The other end of the strip is perforated as shown at 10 while the back beneath this perforation is also perforated but somewhat enlarged as shown at 11. There is, therefore, provided a rimmed socket providing a ledge or rim. 70

A pair of arches 12 are constructed of a resilient metal, such as steel, and one leg 13 of this arch is shortened and reduced to provide a shank adapted to take into the hollow post 7 and provide a shoulder arranged to rest on the end of the post. The other long leg of the arch is reduced to provide a tip 14 arranged to enter the socket, and this tip is notched on one side away from the support of the arch on the post 7, 80 so as to engage with the rim of the socket, while a shoulder is provided at the end of the arch leg. 75

The arch is so formed that when in position on the post, it will normally be in position as shown in dotted lines, Figure 2, so that the tip extends over but beyond the socket. By, however, springing the long leg towards the post and the back, the tip can be sprung into the socket until its notch takes 90 into the rim of the socket in the strip 5, when the arch will be firmly held in position. The end of the tip can be rounded as shown so that the tip can be snapped into the socket by a bearing and springing pressure applied 95 to the arch. The arch itself is preferably resilient enough to permit such springing; however, the mounting of the post on the strip 5 is such that this post and strip can spring to permit such engagement. This 100 strip provides a firm supporting base with the arch, its post and socket, so as to provide a stiff back base. It will, of course, be understood that the arch tip can be disengaged from the socket by a reverse movement thereof as will be readily understood. The shoulder 8 as well as the other metal parts are covered by the covering 3 so as to conceal all metal base parts and present a 105 neat and attractive appearance. 110

The provision of the arch permits the leaves 15, which are perforated for that purpose, to be not only retained in the back of the binder, but also permits them to be 5 turned over the arch and on the other leg, as required. In some cases, however, this arch is not required where, for instance, the leaves are only to be held on one of the sides of the back. Accordingly the post 7 10 is threaded to receive the threaded shank 16 of a knurled head 17. Accordingly by removal of the arches, the latter can be replaced by the retaining heads 17 and vice versa. It will, of course, be understood that 15 the shanks 13 of the arches are smooth and of sufficiently small diameter to permit these shanks to be readily slipped into the threaded posts.

It will, therefore, be seen that the invention 20 accomplishes its objects. A binder is provided which is not only simple in construction, but effective in its action and cheap to manufacture. The interchangeable application of the arch or the retaining 25 head permits this binder to be used for varied purposes. The retaining means for the leaves is not only rigid and strong, but the base is entirely concealed, so as to present a neat and attractive appearance.

30 It is obvious that various changes may be made in details of construction without departing from the spirit of this invention; it is, therefore, to be understood that this in-

vention is not to be limited to the specific details shown and described.

35

Having thus described the invention, what is claimed is:

1. A loose-leaf binder comprising, a back provided with a base strip having a socket, a post on said strip, and an arch having 40 one leg cooperating with said post and having its other leg formed to be sprung into retaining engagement with said socket by springing said arch.

2. A loose-leaf binder comprising, a back 45 provided with a base strip having a socket, a post on said strip, and an arch one of whose legs has a bearing in said post and whose other leg is formed to be sprung into retaining engagement with said socket by 50 springing said arch.

3. A loose leaf binder comprising, a base provided with a socket, a post on said base adapted to receive a retaining head, and an arch adapted to connect with said post and having a tip adapted to engage said socket. 55

4. A loose leaf binder comprising, a base provided with a socket, a threaded post on said base adapted to receive a threaded retaining head, and an arch adapted to connect with said post and having a tip adapted to engage said socket. 60

In testimony whereof I affix my signature this 6th day of May, 1922.

JOHN J. POTT.
